UNITED STATES PATENT OFFICE.

JERRY C. SHANNON, OF SPRINGFIELD, WEST VIRGINIA.

WOVEN-WIRE GRIP.

1,044,929.

Specification of Letters Patent.

Patented Nov. 19, 1912.

Application filed May 4, 1911. Serial No. 624,939.

To all whom it may concern:

Be it known that I, JERRY C. SHANNON, a citizen of the United States, residing at Springfield, in the county of Hampshire and 5 State of West Virginia, have invented new and useful Improvements in Woven-Wire Grips, of which the following is a specification.

My present invention relates to improvements in grips applicable to woven and other fencing for the purpose of tensioning or stretching the same, and it is the primary object of the invention to provide an improved grip of this character which is 10 relatively inexpensive and capable of being applied and locked with facility to the fencing or structure to be stretched, the grip being so constructed that it can obtain and maintain a firm hold upon the woven 15 wire, and the operations of locking and unlocking it may be accomplished easily and quickly.

To these and other ends, the invention consists in certain improvements, and combinations and arrangements of parts, all as will be hereinafter more fully described, the novel features being pointed out particularly in the claim at the end of the specification.

30 In the accompanying drawing:—Figure 1 is a perspective view of a woven wire grip constructed in accordance with my present invention; Fig. 2 represents a side elevation of the grip as viewed from the left in Fig. 35 1; Fig. 3 is a detail sectional view of one end of the grip showing one of the locking wedges and its coöperative loop; Fig. 4 represents a transverse sectional view through the grip showing the action of one of the 40 locking wedges and its coöperative loop; and Fig. 5 shows in perspective the two members of the grip in separated relation.

Similar parts are designated by the same reference characters in the several views.

45 In the accompanying drawing, I have shown the preferred embodiment of my invention, although it will be understood that certain modifications and changes may be made in the details and in the relative arrangement of the parts. In the present instance, the grip is composed of two clamping members 1 and 2. These members may be composed of strips of wood or iron of appropriate strength and the length of the 50 grip may be varied to meet the requirements of different conditions. In using the

grip in connection with fencing, the two clamping members are placed at opposite sides of the fencing and when compressed or forced together by mechanism to be hereinafter described, they obtain a firm hold upon the fencing. In order to enable the grip to obtain a positive or non-slipping hold upon the fencing, the operative faces of the two clamping members may be provided with strips of metal or suitable material 3 and 4, these strips being arranged in alternating relation and secured to the faces of the respective members so that when the clamping members are brought together, the fencing will be bent slightly and, hence, slipping of the fencing between the clamping members is prevented. In using the grip for the purpose of stretching fencing or other woven wire, one of the 60 clamping members (the member 1 in the present instance) may be provided with eyes 5 for the attachment of a suitable fence-stretching device which, however, forms no part of the present invention.

The present invention provides simple and improved means for effectively forcing together and locking the clamping members of the grip whereby the locking and unlocking of the grip may be accomplished quickly 65 and easily, and the grip may be applied and removed with facility relatively to the fencing. In the present instance, one of the clamping members is provided with a suitable number of loops or their equivalents, 70 and the other clamping member is provided with a corresponding number of wedges which, when operated, will force together the clamping members and maintain them in compressed condition until released. In 75 the particular form of mechanism shown, the member 1 is provided with a set of two loops 6 while the member 2 carries a corresponding set of locking wedges 7. Each loop is preferably composed of a doubled 80 rod of metal, the longer arm 8 of which extends through the clamping member 1 and is secured adjustably by means of a nut 9 which is threaded upon its end, while the shorter arm 10 of the loop rests in a bore 85 or opening 11 which is formed in the clamping member 1. In order to keep the loop 6 in proper operative position so as to receive with certainty its respective locking wedge, a compression spring 12 is preferably placed 90 in the bore 11 and bears against the end of the short arm 10 of the loop, this spring 95

holding the nut 9 against the rear face of the clamping member 1. Each wedge is preferably formed by the tapered or inclined end of a rod, the several rods being suitably connected to a single or common operating handle or lever 13, this lever being pivoted on a bolt or other fulcrum 14 which is preferably carried by the clamping member 2, and the several wedges 7 are positioned so as to properly enter the eyes formed by the loops, staples 15 being provided for the purpose in the present instance, and metal strips or plates 16 may be secured to the outer face of the clamping member 2 to afford suitable bearings for the respective wedges. The clamping member 2, it is to be understood, is provided with slots or openings 17 through which the locking loops 6 extend, and when the clamping members are applied to the fencing or other woven wire, these loops project through the clamping member 2 and are in substantial alinement with the wedges. Operation of the handle 13 will then serve to move all the wedges into locking engagement with their respective loops and the clamping members will be thereby forced together firmly. When the operating handle 13 is moved into fully locked position, those portions of the rods behind the wedges will engage the locking loops and the grip cannot be unlocked except by moving the operating handle toward unlocked position, or, in other words, the grip will be maintained in locked condition without the necessity of the operator holding the handle. It is to be understood that any suitable number of locking loops and wedges may be used, two being shown in the present instance as an example, and by using a plurality of locking devices which are actuated by a common handle, all portions throughout the length of the grip are forced together firmly and uniformly so that a positive grip throughout the extent of the wire or fencing is obtained. Preferably, the operating handle is movable in a plane parallel to the plane of the gripping faces of the clamping members, as this facilitates the manipulation of the device and avoids breakage of its parts.

I claim as my invention:—

A woven wire grip comprising, in combination, a pair of coöperative bars having opposed clamping faces, a loop having a shank extending through one of said bars and having an abutment coöperative with such bar, said loop also having a parallel shank engaging in a socket in the bar with which said abutment coöperates, a spring contained in said socket and coöperative with the respective shank of the loop to retain said abutment in engagement with the respective bar, and means coöperative with said loop to force said bars together and clamp the wire between them.

In testimony whereof I have hereunto set my hand in presence of two subscribing witnesses.

JERRY C. SHANNON.
